TEMPORARY BINDER.

Application filed November 28, 1922, Serial No. 603,820, and in Sweden December 29, 1921.

The present invention relates to that class of temporary binders in which the back comprises two sections of sheet metal, which are hinged together, and the invention consists in a special construction of these sections, the locking device and the attachments for the threaders.

Embodiments of the invention are shown in the accompanying drawings. Figures 1 and 2 are an inner side view and end view respectively of the back sections in closed position. Fig. 3 is a longitudinal sectional view taken on line 3—3 of Fig. 1. Fig. 4 is a rear view of the upper part of the binder back. Fig. 5 is a front view of the same. Fig. 6 is a section on the line 6—6 of Fig. 5. Fig. 7 is a cross section on the line 7—7 of Fig. 5 on an enlarged scale.

Both back sections 1 and 2 are as stated manufactured of metal sheet and the adjacent edges of the same are provided with sleeves 4 projecting between each other and surrounding a hinge pin 3 in ordinary manner.

In the adjacent longitudinal edges of the back sections there are cut a number of slits so as to form tongues, every other tongue of each section being curled to form a sleeve and the other tongues being either cut away or left unbent, thereby forming stops 25. These stops are, however, provided at their inner ends with shoulders 10 of substantially semi-circular cross section and frictionally engaging the sleeve of the opposite hinge plate 11. In closing the back the stops 25 of one back section abut against the inner surface of the other back section, thereby causing a mutual stability of the back sections and forming simultaneously some-

what resilient lugs, which limit the closing movement and make an active resistance to a deformation of the binder back. The back can be manufactured of thin steel-plate. Those edges 5 of the plate sections, which are formed by the tongues being removed are bent inwardly so as to closely abut against the sleeves of the opposite plates.

The plate sections are provided with transverse flanges 6 suitably formed by bending the end edges of the plate sections, whereby the rigidity of the plate sections is increased, and said flanges further constitute protective members for the covers, when the latter are slid over a supporting surface.

Moreover, the plate sections are provided with longitudinally extending flanges or side parts 16 from which the tongues 19 are stamped out, said tongues serving to attach the plate sections to the cover 17 and also to attach the plates 8, 9 to the side parts 16. Pins 7 are fixed to the plates 8, 9. These tongues after having been stamped out, are at first bent inwardly and then threaded through holes in the covers and plates 8, 9 and finally the tongues are further folded so as to lie against the covers and the plates 8 and 9 respectively.

The plate 9 is provided with an integral projection 21 directed towards the other plate 8. The plate 8 is provided with an integral projection 22 directed towards said projection 21. When the binder is closed, both the said projections lie against or near each other, as shown in Fig. 2. To the inner side of the projection 22, the locking catch 11 is pivotally secured by means of the pin 12. When closing the covers the bent free end of the locking catch passes into a recess of the outer bent end of the projection 21 and is caught by one edge of said recess in known manner. A latch lever 13 is connected by means of a wire 14 with the locking catch 11 and the connection between said parts 11 and 13 is such that when actuating the lever a drawing is exerted on the wire so as to disengage the catch. By this means a very thin wire may be employed in contradistinction to the known locking devices of this class, where the connecting part between the lever and the catch is moved towards the latter upon opening the lock. 15 designates the spring, which tends to bring the catch into locking position.

The stops 25 provide a certain resilient resistance to the very last portion of the closing movement thereby causing the locking catch to actively press upon the inside of the bracket 21 in the closed position of the binder. The stops also prevent any play of the back sections in the closed position.

From the plate 8 extends, at an angle thereto, a long plate 23 integral with the plate and the bracket 22, and forming with the latter a casing for the locking device, the outer end of said plate 23 being bent so as to form a channel shaped part 26, to which the said latter lever 13 is pivotally attached.

On the rear side, the plate sections 1 and

2 are suitably provided with slightly recessed parts for receiving pieces of pasteboard or the like, which for instance are riveted and on which labels may be applied.

5 Another more suitable arrangement to facilitate placing labels or docket strips on the binder back, is shown in Figs. 4-7. In each of the plate sections, an opening 33 lengthened in the vertical direction is cut, 10 the opening of one plate section having the same form and size and being situated at the same height as the opening in the other plate section. The opening is closed by means of a pasteboard sheet 34, which is of 15 greater length and breadth than the opening and is stamped in such a way that an annular shoulder is formed between the edges and the body of the pasteboard sheet 34, whereby a depression is formed on the inner 20 side of the sheet 34 as clearly shown in the Figs. 6 and 7. The disk 34 is inserted from the inside of the binder, the main part thereof then projecting into the opening and its edges abutting against the inner side of 25 the edges of the opening. The pasteboard sheet is held by means of tongues 36, cut from the plate sections, extending through holes in the edges of the pasteboard sheet and pressing against another sheet 35 of 30 metal or any other suitable material.

This sheet 35 is of the same or about the same length and breadth as the recess on the inside of the sheet 34 so that the plate 35 exactly or at least nearly exactly fits into 35 this recess. Preferably the thickness of the plate 35 has such a size that when the plate is in the secured position, the inner surface thereof about coincides with the inner surface of the edges of the sheet 34.

40 The manner of placing the pasteboard sheets in position may be clearly understood from the foregoing and the following. The tongues 36 in the beginning project inwardly. The pasteboard sheet is placed in 45 position by threading the holes of the same on the tongues. Then the metal sheet 35 is placed in position, whereupon the tongues 36 are bent to grasp the plate 35. The pasteboard sheet is suitably given such form when 50 being stamped that its outer surface, when the sheet is in the secured position, substantially coincides with the outer surface of the corresponding plate section.

What we claim as new and desire to secure by Letters Patent of the United States of America is:

1. A temporary binder, the back of which is made of two sections of plate hinged together, said sections being provided with 55 transverse flanges at the ends, the rear parts of the covers which are hinged to the main parts thereof extending along the inside of the said back sections, said transverse flanges forming protective members for the end 60 edges of the covers of the binder.

2. A temporary binder, the back of which is made of two sections of plate, said sections being angle-shaped, seen from the end, and having transverse flanges at the ends, the rear parts of the covers which are hinged to the main parts thereof extending along the inside of the said back sections, said flanges being made integral with the main part of the sections and forming protective members for the end edges of the 70 covers of the binder.

3. A temporary binder, the back of which is made of two sections of plate, hinged together, the hinges being formed by tongues, spaced apart and cut out from the plate sections and then bent round to form knuckles, the plate section edges between said tongues being rounded and abutting closely against the opposite knuckles of the hinges.

4. In a temporary binder the back of which is made of two sections of plates which are hinged together by means of hinge knuckles and a pintle passed through the knuckles, and which are provided with tongues, which are made integral with and project from the adjacent edges of the back sections and abut against the innerside of the opposite back section in the closed position of the back, and at their roots are provided with longitudinal knuckles grasping 95 the opposite knuckles.

5. A temporary binder, the back of which is made of only two sections of plate, hinged together, said plate sections being provided at the inside of their lateral parts with plates, to which threaders are attached, two brackets being made integral with the said plates respectively, said brackets abutting against each other in the closed position of the binder, a catch belonging to a locking mechanism being pivotally mounted in the one bracket, said catch being influenced by springs and actuated by a finger key, the locking catch in the locked position grasping 100 an edge of the other bracket.

6. A temporary binder, the back of which is made of only two sections of plate, hinged together, said sections being provided at the inside of their lateral parts with side plates, serving as attachment for threaders, two brackets being made integral with the said plates respectively, said brackets abutting against each other in the closed position of the binder, a catch belonging to a locking mechanism being pivotally mounted in the one bracket, said catch being influenced by springs and actuated by a finger key, the locking catch in the locked position grasping 110 an edge of the other bracket, a plate part 115 projecting from and being made integral with the one of said side plates and the bracket of the latter, said plate part together with its bracket forming the casing of the locking mechanism.

7. A temporary binder, the back of which 120

is made of only two sections of plate, hinged together, said sections being provided at the inside of their lateral parts with side plates, serving as attachment for threaders, two 5 brackets being made integral with the said plates respectively, said brackets abutting against each other in the closed position of the binder, a catch belonging to a locking mechanism being pivotally mounted in the 10 one bracket, said catch being influenced by springs and actuated by a finger key, the locking catch in the locked position grasping an edge of the other bracket, a plate part projecting from and being made integral 15 with the one of said side plates and the bracket of the latter, said plate part together with its bracket forming the casing of the locking mechanism and means for releasing the locking catch by exerting a drawing in 20 the connecting part, through the aid of the finger key, said connecting part consisting of a thin thread.

8. A temporary binder in which the back is made of two sections of sheet metal, hinged 25 together, and which is provided with an opening which is closed at the inside of the sheet metal by a flat member of a material, on which designations can be printed and on which a label can be affixed.

30 9. A temporary binder in which the whole back is made of two sections of sheet metal and which is provided with a number of openings, each of which is closed at the inside by a sheet of pasteboard, on which a 35 label can be affixed and designations can be printed.

10. A temporary binder, in which the back is only made of two sections of sheet metal hinged together and in which the back is 40 provided with an opening, which is closed by a sheet of material which is fixed in its position and on which designations can be printed, said sheet having a greater length and breadth than the opening and abutting 45 with its edge parts against the inner side of the back.

11. A temporary binder, in which the back is made of sheet metal and provided with an opening which is closed by a sheet of paste- 50 board, said sheet being secured to the inside of the back by tongues bent inwards and cut out from the back plate.

12. A temporary binder, in which the back is made of sheet metal and provided with an 55 opening, which is closed by a flat member of a material on which designations can be printed and a label can be affixed, said member being secured to the back by tongues bent inwards and cut out from the back 60 plate, said member on its marginal parts be-

ing provided with a number of openings through which the tongues are passed.

13. A temporary binder in which the back is provided with a number of openings, each of which is closed by a flat member of a material 65 on which designations can be printed, and a label can be affixed, a second flat member of plate material secured to the back and abutting against the inside of the first flat member, the second flat member engaging 70 with its edges between the tongues and the first flat member.

14. A temporary binder, in which the back is provided with an opening which is closed by a sheet flat member of suitable material, 75 on which designations can be printed, a second flat member, secured to the back and abutting against the inside of the first flat member.

15. A temporary binder, in which the back is provided with an opening which is closed by a label sheet of a material, on which designations can be printed, the first sheet being pressed so as to form a shoulder between its marginal parts and the remaining part or main part of the same, so that the main part projects into the opening. 85

16. A temporary binder, in which the back is provided with a number of openings each of which is closed by a label sheet of a material, on which designations can be printed, the first sheet being pressed so as to form a shoulder between its marginal parts and the remaining part or main part of the same, so that the main part projects into the opening, 95 the second sheet having the same or nearly the same length and breadth as the main part of the first sheet so that it fits into the cavity formed on the outer sheet on account of the said shoulder. 100

17. A temporary binder, in which the back is made of sheet metal and provided with a number of openings each of which is closed by a label sheet of a material, on which designations can be printed, said sheet being secured to the back by tongues bent inwards and cut out from the back plate, said sheet on its marginal parts being provided with a number of holes through which the tongues are passed, the said sheet 110 being given such a form upon pressing that in its secured position the outside of the same coincides or nearly coincides with the outside of the respective plate section.

In testimony whereof we affix our signatures. 115
